[57] CLAIM

The ornamental design for a literature holder, as shown and described.

DESCRIPTION

FIG. 1 is a perspective view of a literature holder showing my new design;

FIG. 2 is a front elevational view thereof;

FIG. 3 is a side elevational view thereof;

FIG. 4 is a rear elevational view thereof;

FIG. 5 is a top plan view thereof;

FIG. 6 is bottom plan view thereof.

The broken line showing of a literature holder in FIGS. 1, 2, 3 and 4 is for illustrative purposes only.
